CLOTHES HANGER

Earl S. Tupper, Smithfield, R. I.

Application October 25, 1956, Serial No. 43,529

Term of patent 14 years

(Cl. D80—8)

Fig. 1

Fig. 2

I claim:

The ornamental design for a clothes hanger, substantially as shown.
